CLAIM

The ornamental design for a valve housing, as shown and described.

DESCRIPTION

FIG. 1 is a perspective view of a valve housing of the new design;

FIG. 2 is a front elevational view of the valve housing of FIG. 1;

FIG. 3 is a rear elevational view of the valve housing of FIG. 1;

FIG. 4 is a left side elevational view of the valve housing of FIG. 1;

FIG. 5 is a right side elevational view of the valve housing of FIG. 1; and,

FIG. 6 is a top plan view of the valve housing of FIG. 1.

The portions of the Figures shown in broken lines are not part of the claimed design and are for illustration only.

1 Claim, 4 Drawing Sheets
